INVENTOR

Franklin LeRoy Rogers

BY Charles L. Reynolds

ATTORNEY

UNITED STATES PATENT OFFICE

FRANKLIN LE ROY ROGERS, OF SEATTLE, WASHINGTON

DESIGN FOR A CLOTHESPIN BASKET

Application filed January 28, 1931. Serial No. 38,467. Term of patent 3½ years.

To all whom it may concern:

Be it known that I, FRANKLIN LE ROY ROGERS, a citizen of the United States, residing at Seattle, in the county of King and State of Washington, have invented a certain new, original, and ornamental Design for Clothespin Baskets, of which the following is a specification, reference being had to the accompanying drawings, forming part thereof.

I claim—

The ornamental design for a clothespin basket, as shown.

FRANKLIN LE ROY ROGERS.
